UNITED STATES PATENT OFFICE.

JOHN LEE McDOWELL, OF BERWICK, PENNSYLVANIA, ASSIGNOR TO AMERICAN CAR AND FOUNDRY COMPANY, OF NEW YORK, N. Y., A CORPORATION OF NEW JERSEY.

MINE-CAR RUNNING-GEAR.

1,256,148.

Specification of Letters Patent. Patented Feb. 12, 1918.

Application filed September 5, 1917. Serial No. 189,860.

To all whom it may concern:

Be it known that I, JOHN LEE McDOWELL, residing at Berwick, Columbia county, State of Pennsylvania, and being a citizen of the 5 United States, have invented certain new and useful Improvements in Mine-Car Running-Gears, of which the following is a full, clear, and exact description, such as will enable others skilled in the art to which it 10 appertains to make and use the same, reference being had to the accompanying drawings, which illustrate the preferred form of the invention, though it is to be understood that the invention is not limited to the exact 15 details of construction shown and described, as it is obvious that various modifications thereof within the scope of the claims will occur to persons skilled in the art.

In said drawings:

20 Figure 1 illustrates one form of the outer end of my improved wheel and the means for attaching it to the axle;

25 Fig. 2 is a detailed sectional view of the lower part of the journal box of Fig. 3 and illustrates the sliding relation of the projection from the lubricant-retaining cap to the slot in the journal box in which it slides; and

30 Fig. 3 is a vertical section of my improved mine car running gear and illustrates a modified form of the outer end of the hub and the wheel attaching means.

An object of the invention is to provide a 35 running gear assembly comprising a simple, economical and durable wheel consisting of a minimum number of parts which may be readily secured in position upon an axle, retain a roller bearing assembly in position within a roller bearing chamber of the wheel, 40 provide means for locking the roller bearing assembly in position within the wheel hub, which means presents a smooth, vertical face to the roller bearing assembly when the wheel is in operative position, and a smooth bearing surface at the rear side of the wheel hub 45 to coöperate with a journal box secured to the car and adapted to coöperate with friction-reducing means and lubricant-retaining means properly conjoined with the wheel, as 50 hereinafter more particularly described.

Another object is to provide means to permit the wheel hereinbefore referred to to adjust itself to inequalities of the track surface, which means may be employed with

wheels of any type and for any service, but 55 particularly in connection with mine cars, to which the invention especially relates.

A further object of the invention is to provide lubricant-retaining means adapted to coöperate with a peculiar form of journal 60 bearing box, which permits one or all of the wheels, independently or otherwise, to drop by gravity in passing over depressions in the track surface, thereby preventing derailment of the cars. 65

Referring particularly to the parts, A is the tread, B the spokes and C the hub of a mine car wheel which is provided with a closed outer end wall D forming an extension of the hub, though cast integral therewith 70 and being perforated at E, E, preferably by alined openings to permit insertion and removal of a cotter pin, as F, though it is evident that other means of securing the wheel in position may be substituted for the cotter 75 pin; as for example the bolt F' which co-operates with an annular groove G cut in the outer end of the axle H instead of passing through a perforation in such axle, as shown in Fig. 1. In either case, however, it is preferred that the outer wall of the hub be provided with a screw-threaded orifice I, which may be utilized for temporary connection therewith of a grease gun or lubricant supplying tool from which lubricant may be injected into the lubricant 85 chamber J when desired, and as a proper lubrication of mine car wheels is a very material factor, contributing to the life of such wheels in service, it is advisable that, regardless of whether the cotter pin F or bolt F' is employed to lock the wheel in position on the axle, it will be convenient at all times to replenish the supply of lubricant within the reservoir J without removing the wheel 95 from the axle, and it is also advisable to form the outer end of the hub of the wheel closed; that is, of a single wall cast with the major portion of the hub, as for example in Patent No. 321,590 of July 7, 1885. 100

In the type of wheel shown in the drawing, in which roller bearings of the well known Hyatt type are illustrated, it is advisable to provide a vertical plane surface, to serve as an abutment for the outer end of 105 the roller bearing assembly, which serves as a stop to prevent movement of such roller bearing assembly longitudinally within the

wheel hub, and it is also important that there shall be no annular depressions, adjacent the ends of such roller bearing assemblies, into which the annular rings K' of the roller bearing cages may drop, become locked and cause destruction of such assembly. To that end, and to provide a suitable wearing face for the rollers K , a high-carbon steel sleeve L is inserted within the wheel hub, which 5 sleeve extends preferably into contact with the rear face of the wall M formed intermediate the ends of the hub. This wall may be formed, as shown in Fig. 1, dividing the lubricant chamber J of predetermined 10 diameter from a smaller roller bearing chamber K^2 , or the wall may consist of the face M of Fig. 3, as may be desired, but in either instance the sleeve is positioned preferably so as to rest in approximate contact 15 with the rear face of such wall. The axle H may be formed from any suitable material, but it is preferred to use a heat-treated axle where the hardened steel rollers K are employed, though I do not wish to 20 be limited in this respect, as it is obvious that a cold-rolled steel axle may be used, if desired, and might be employed where cold-rolled steel rollers are substituted for the 25 high-carbon steel rollers K , referred to.

30 Various means have been provided at the inner end of the wheel hub for retaining roller bearings in position, such as flanged collars secured within the roller bearing chamber of the hub and locked in position 35 by means of rivets, or other fastening means, projected through such flanged collars and the metal of the inner hub extension P , but these are objectionable because, first, of the multiplicity of parts and, second, the holes 40 formed in the hub weaken the hub and there is always the possibility of cracking the hub while heading the rivets thus employed. To overcome these objections and to strengthen the hub rather than to weaken it, the cap Q 45 is employed which cap comprises a cup-shaped member including the flange 1 extending longitudinally of the wheel hub and parallel with the axle and the flange 2 which extends inwardly from the flange 1 and provides plane smooth vertical faces, 50 one on its inner side and one upon its outer side, for the purposes hereinafter referred to.

The cap Q is, as shown in the drawing, of considerable thickness and is a valuable adjunct in mine car service because of the fact 55 that the flange 1 projects for some distance outwardly from the outer face of the hub C and serves as a stop to prevent the passage of dust in between the wheel and the journal box. It is well known that the fine dust, 60 with which the air is impregnated in coal mines, drops by gravity upon the hub of the wheel, as ordinarily constructed, and unless some means is provided to permit this to fall off during the rotation of the wheel 65

it will find its way into the bearings, thereby leading to an early destruction of the wheel assembly, and while flange 1 of the cap serves as a reinforcing member for the inner end of the hub, it also serves as a 70 means to retard and practically prevent the flow of dust from the normal face of the hub into the bearings, thereby prolonging the life of the wheel. The flange 2 extending inwardly, as shown, is provided on its inner side with a smooth vertical face 3 against which the end ring 4 of the roller bearing assembly may travel without danger of disintegration of the roller bearing assembly. While the rear face 5 of the flange 2 is also 75 a smooth plane surface adapted, if desired, to contact with the outer face 6 of the journal box, it is preferred that a washer 7 contact with such face 5, which washer is free to rotate upon the axle H and between the 80 face 5 of the cap Q and the journal box, except in instances where an auxiliary cap R provided with a rearwardly extending lug S is used, as hereinafter explained.

The wheel hub is cast generally as shown 90 in the drawings with this difference, however, that when the hub is cast the portion P is formed of greater thickness than is illustrated so as to provide such thickness of metal as will result in a casting of the 95 proper degree of hardness, after which it is preferred that some of this metal shall be cut away, in a suitable machine, to reduce the external diameter of the extension P and form on its outer circumference a smooth 100 surface upon which the cap Q may be shrunk in the position shown. This trimming or machining is done in the process of production after which the sleeve L is inserted, the 105 roller bearing assembly is placed in the sleeve within the roller bearing chamber of the wheel, the cap Q is properly positioned while hot and in cooling it shrinks, upon the portion P of the hub. It is preferred that the internal diameter of the cap and the external diameter of the portion P of the 110 wheel shall be so nearly uniform that a secure connection will be established between the hub and the cap due to the shrinkage of the latter. The outer portion of the wall 115 3 of the cap preferably rests in approximate contact with the rear edge portion P of the hub and outer end of the sleeve L . When this is done it is obvious that the cap will be retained in position practically during the 120 life of the wheel and serve as means for reinforcing the inner portion of the hub, as an end wall to retain lubricant within the hub, to secure the roller bearing assembly in position, and to provide a smooth friction-reducing wear plate between the hub and the next adjacent member of the wheel assembly, whether such member be the washer referred to, the face 6 of the journal box, or any means interposed between them. The 125 130

portion P' of the hub may be tapered with its lesser diameter nearer the center of the hub to additionally assist in holding the cap Q when it is shrunk thereon.

5. Coöoperating with the parts referred to, there is provided a washer 9 which is cast in position within the lubricant reservoir at the outer end of the hub and this washer 9 serves as a means for reducing friction between the cotter pin F and the wall M where a cotter pin is employed.

It is desirable that a sufficient quantity of lubricant shall be supplied to the wheel to lubricate not only the roller bearings, but 15 also permit a flow of a minimum quantity of such lubricant as may be entrained by the axle rearwardly or toward the car body and journal box. This lubricant finds its way along the axle in a sufficient quantity to prevent wear between the flange 2 of the cap and the washer 7.

In some instances it may be desirable to employ additional means to prevent the loss of lubricant at the inner end of the wheel 25 hub, or to retard the egress of lubricant thereat, and for that purpose the auxiliary cap R is provided, which cap may be used with any type of wheel hub, though preferably with the one illustrated in the drawings, and comprises the pressed metal packing-retaining annulus 10 provided with an inturned flange 11 and vertical rear wall 12 and within which is locked the packing 13 of hair felt or other suitable lubricant-absorbing-and-retaining material.

As it is preferred that the auxiliary cap R shall be relatively fixed, that is that it shall not rotate with the wheel, it is provided with a rearwardly extending lug S which 40 is seated in a slot T in the journal box U, which slot is open at its lower side, as shown, and the journal box is provided with a relatively elliptical opening for the axle H, providing a clearance 15 between the bottom of the axle and the upper face 16 of the lower portion 17 of the journal box. The object of this is to permit each wheel to 45 drop independently of the others and below the normal plane of the track to accommodate depressions or inequalities in the track surface.

What I claim is:

1. In combination, an axle, a car wheel mounted thereon, and a journal box entered by said axle and provided with an axle-opening forming a clearance below said axle permitting the wheel and axle to guidedly drop from and return to a journal box-supporting position in response to vertical displacement of said wheel in service, while the wheel is on the axle.

2. In combination, a wheel hub having an open inner end, a journal box, a cap extending radially and longitudinally of said inner hub end and positioned between the

latter and said journal box, and an axle projecting through said journal box and cap to have a bearing in said hub, said journal box having axle clearance and guiding means permitting said axle and hub to drop.

3. In combination, a wheel hub having an open inner end, a cap telescoped with that hub end and having a plane radial surface, a journal box provided with a plane surface 75 parallel to said cap plane surface, an axle in said journal box and hub, a washer loosely mounted on said axle between said plane surfaces, there being an elongated axle passage in said journal box affording clearance 80 to permit the axle to drop below its normal position therein.

4. In combination, a wheel hub having an open inner end, a cap telescoped with that end, a journal box, said cap and journal 85 box having parallel plane surfaces, an auxiliary cap between said plane surfaces into which auxiliary cap the first cap projects, lubricant-absorbing-and-retaining material held between both caps, and an axle extending into said journal box and wheel hub.

5. In combination, a wheel hub, a journal box adjacent an end thereof and provided with guiding means and an axle passage, a 95 lubricant-retaining cap between said hub and journal box formed to slidingly engage said guiding means, and an axle of less diameter than the height of said axle passage, said axle extending into said journal box 100 and hub and adapted under the influence of the latter to drop below its normal position in the journal box axle passage.

6. In combination, a wheel hub, a journal box provided with an axle passage and a 105 slot, a lubricant-retaining cap between said hub and journal box and provided with a projection entering said journal box slot, and an axle passing through said journal box and cap and entering said hub, said axle and cap projection being slidable vertically of said journal box.

7. In combination, a wheel hub with a chamber having an open inner end and an outwardly disposed wall containing an axle 115 bore, a journal box having a slot, a cap extending over the hub inner end and having a projection slidable in said slot, an axle vertically slidable in said journal box and extending beyond the outwardly disposed 120 wall of said hub chamber, friction-reducing means in said chamber, and axle-carried means co-acting with said wall to retain the parts in correlative positions.

8. In combination, a wheel hub with a 125 chamber open at the inner end of said hub and outwardly terminated by a shoulder-forming wall, a sleeve lining said chamber, an axle-bore-containing cap frictionally telescoped with the open end of said hub, a 130

journal box provided with a slot, a lubricant-retaining cap interposed between the first cap and said journal box and having an extension slidable in the journal box slot, an 5 axle vertically slidale in said journal box and friction-reducing means between said sleeve and axle and opposed by the first cap and said shoulder-forming wall.

In witness whereof I have hereunto set my hand in the presence of two witnesses.

JOHN LEE McDOWELL.
